UNITED STATES PATENT OFFICE

2,570,426

POURING ATTACHMENT FOR PAINT CANS

William W. Cassidy, Englewood, Colo.

Application October 7, 1948, Serial No. 53,230

1 Claim. (Cl. 222—570)

1

This invention relates to attachments for paint cans and more particularly to a device which facilitates pouring of paint from a can.

It is common practice to retain paint, especially in the smaller quantities, such as gallons, half-gallons, quarts, or less, in cans having a circumferential groove at the top thereof, into which the lid frictionally fits. The pigment in paint separates from the vehicle and settles to the bottom of the can quite rapidly, hence, it is almost always necessary for the user of the paint to mix it to uniform consistency before use. Mixing is sometimes effected by stirring with a stick or the like, but the most effective manner is by pouring the paint back and forth between two cans. When the paint is poured from the can, it must flow over the groove previously mentioned and a certain amount of paint will be retained therein after mixing, or other procedure involving pouring of the paint, is completed. The user often omits to clean the groove and reapplies the friction lid to the partially paint filled groove. An effective seal cannot be obtained when this is done and as a result air enters the can and dries the paint. The user often finds, when it is later desired to use the remaining paint, that it has dried to such extent to be rendered useless. Paint is quite expensive; hence, this may result in considerable monetary loss.

Also, during the process of pouring the paint, a certain amount thereof will almost invariably run down the outside of the can onto the can label and if this is not carefully cleaned, the information contained on the label will be obliterated when the paint dries. This, of course, renders difficult later identification of the exact contents of the can.

The careful painter recognizes the importance of a tight seal of the can lid and carefully cleans the groove before reapplying the lid. This groove is relatively deep and quite narrow, however, and it is difficult to properly clean it and entails an unnecessary loss of time in performing the cleaning operation.

The principal object of the invention is to obviate the disadvantages above mentioned by the provision of an attachment for a paint can which prevents the paint from entering the can groove during pouring.

Another object is to prevent paint from running down the outside of the can during pouring.

A further object is to construct the attachment in such manner that the painter has more effective control of the pouring of the paint.

2

Other objects are to provide an attachment which is simple in construction, may be inexpensively manufactured, and will effect considerable saving in time to the user, and also a monetary saving.

The above objects and any others that may appear as the description proceeds are attained by means of a construction and an arrangement of parts that will now be described in detail and reference for this purpose will be had to the accompanying drawing where the invention has been illustrated, and in which:

Figure 1 is a top plan view of one embodiment of the invention shown in position on a paint can, the latter being shown by dotted lines;

Figure 2 is a section taken on line 2—2, of Figure 1;

Figure 3 is a section taken on line 3—3, of Figure 1;

Figure 4 is a top plan view of another embodiment of the invention;

Figure 5 is a section taken on line 5—5, Figure 4;

Figure 6 is a section similar to Figure 3, but showing another embodiment of the invention;

Figure 7 is a section similar to Figure 3, but showing a further embodiment of the invention; and

Figure 8 is a side elevation, portions being broken away, showing any of the embodiments in use.

Referring in detail to the drawing there is shown in Figures 1 to 3, a conventional paint can 10 having a conventional peripheral friction groove 11 at its top, the friction lid which normally engages within this groove having been removed. The friction groove just mentioned is endless and U-shaped in cross section and extends adjacent the periphery of the can at one end thereof. The attachment 12, which may be constructed of sheet metal, has a slightly dished portion 13 which is bounded by a circular side 14 and a chordal edge 15. The circular side is provided with a downwardly extending rim 16, as best shown in Figure 3, which is so proportioned to groove 11 that it will frictionally fit therein in the same manner as the can lid normally retained in this groove. An aperture 17 is provided in the dished portion adjacent the rim which aperture is surrounded by a downwardly extending flange 18 through which paint may pour as will be hereinafter explained. A pouring lip 19 is soldered, or otherwise secured, to the attachment adjacent this aperture and extends

50

laterally of the can to a point beyond the side wall thereof.

In Figures 4 and 5 is shown another embodiment of the invention wherein the pouring lip 19' is formed as an integral part of the attachment rather than as a separate part as shown in Figures 1 to 3. The lip also carries upstanding flanges 20 along its lateral edges which prevent any paint from running over the lateral edges and aid in directing the paint to the outer edge of the lip. The downwardly extending rim 16 fits within the can groove 11 in the same manner as previously explained in connection with Figures 1 to 3. The top of this rim forms a channel 21 which would permit paint to run along this channel and into the can groove, hence to prevent this undesirable result, this channel is filled with a suitable material, such as a plastic insert 22, which prevents flow of paint along the channel 21. This insert need not extend the full length of channel 21 and if desired the ends, only, of the channel may be suitably plugged. This would permit paint to enter the channel 21 but prevent it from running into the can groove. If paint is left within the groove after use, it would fill such groove and dry therein, thus effecting the same result as filling the groove with the insert previously described.

In the embodiment shown in Figure 6, the attachment is made substantially the same shape as that of Figure 1 except that it is integrally formed of plastic, or the like, rather than sheet metal and rim 16' is solid rather than channel shaped as shown in Figure 1.

In the embodiment shown in Figure 7, the attachment is made of sheet metal as in Figure 1, but the lip 19'' is formed of plastic or other material and is forced into the channel 21 formed in the upper side of rim 16.

When it is desired to use the attachment, the lid of the paint can is removed and the attachment applied to the can groove as previously explained. Another attachment may be applied to an empty can 23, as shown in Figure 8, and the paint is poured from can 10 to can 23. As previously explained, one side of the attachment is chordal at one edge and has an opening 24 through which the paint may enter the can. When the contents of can 10 have been poured into can 23, the process is then reversed and continued, pouring back and forth until the paint is thoroughly mixed. In Figure 8 it will be observed that the portion 13 forms a level dam on the paint can above the level of the paint and the paint must flow through aperture 17. The aperture meters the rate of flow and this rate may be chosen as desired by choice of the size of the aperture. This is a considerable advantage over the former method of pouring over the edge of the can because in that method the rate of flow is solely governed by the manner and rate in which the can is tipped. If the can is tipped too rapidly, spilling of paint is likely to occur and, of course, if pouring is to be at a uniform rate, the can must be carefully and uniformly tipped. With this invention less care is required in tipping because the aperture controls the rate of flow, for example, if the can be tipped too rapidly, instead of spilling paint, the aperture will limit the rate of flow.

It is to be particularly observed that during the pouring, groove 11 of the can is filled by rim 16 and also that lip 19 extends beyond the side of the can. Since the groove is filled, it is apparent that no paint may enter same and any

dripping down the side of the can is eliminated because lip 19 extends far enough therebeyond that drippings, if present, will fall beyond the side of the can. It now becomes apparent that paint may be removed from the can to a point beyond the edge thereof without passing into the friction groove and hence when pouring is completed and the attachment removed the groove is in the same state of cleanliness as existed before the attachment was employed.

The flange 18, previously referred to, serves the purpose of directing drippings back into the can after pouring is completed. The edge 15 may be used to scrape excess paint from a paint brush and the downwardly dished portion 13 provides a drain means which directs any surplus paint back into the can.

The manner of use has been described above in connection with two attachments by way of exemplification, but it will be apparent that one attachment only may be used, if desired. For example, if can 23 has no friction groove, or has a friction groove which the user does not desire to be kept free of paint, he merely applies the attachment to the one can which he desires to reseal. It is also apparent that the attachment will find utility in connection with cans which contain liquids other than paint. Also, while the attachment has been illustrated for use with a circular can, it is apparent that if the can were of other shape, such as square or rectangular, the edge and rim corresponding to circular edge 14 and the rim 15, respectively, would be shaped to correspond with the particular shape of the can.

Having described the invention what is claimed as new is:

An attachment for a friction groove can of the type having a circular U-shaped groove adjacent the periphery of one end thereof, comprising; a plate-like member having a circular edge and a chordal edge, a downwardly extending circular rim on the lower face of said member adjacent said circular edge, said rim being proportioned to engage within the can groove, the plate-like member having a pouring aperture adjacent said rim substantially midway the peripheral length of said rim, said plate-like member being dished downwardly from said rim in such manner that its lowest point is substantially midway the length of said chordal edge, whereby liquid lying on said plate-like member will drain from all portions thereof over said chordal edge at substantially its central portion when the plate-like member is secured to a can having the plane of the open end thereof disposed in a substantially horizontal position.
